(57) **CLAIM**

The ornamental design for a tympanic thermometer, as shown and described.

DESCRIPTION

FIG. 1 is a left elevation view of the tympanic thermometer of the design;

FIG. 2 is a right elevation view of the tympanic thermometer of the design;

FIG. 3 is a front elevation view of the tympanic thermometer of the design;

FIG. 4 is a rear elevation view of the tympanic thermometer of the design;

FIG. 5 is a top view of the tympanic thermometer of the design;

FIG. 6 is a bottom view of the tympanic thermometer of the design; and,

FIG. 7 is an isometric view of the tympanic thermometer of the design.

1 Claim, 6 Drawing Sheets
